[57] **CLAIM**

The ornamental design for a toilet seat handle, as shown and described.

DESCRIPTION

FIG. 1 shows a top view of my design for a toilet seat handle mounted on a toilet seat;

FIG. 2 shows a perspective view of my design for a toilet seat handle;

FIG. 3 shows a top view thereof;

FIG. 4 shows a side view thereof, with both sides being identical;

FIG. 5 shows a rear view thereof;

FIG. 6 shows a front view thereof; and,

FIG. 7 shows a bottom view thereof.

The broken line showing is for illustrative purposes only and forms no part of the claimed design.
